UNITED STATES PATENT OFFICE.

FRED CONRAD, OF MILWAUKEE, WISCONSIN, ASSIGNOR TO AMERICAN LACE PAPER COMPANY, A CORPORATION OF WISCONSIN.

DESIGN FOR A PAPER DOILY.

49,950.

Specification for Design.

Patented Nov. 28, 1916.

Application filed October 12, 1916. Serial No. 125,337. Term of patent 7 years.

To all whom it may concern:

Be it known that I, FRED CONRAD, a citizen of the United States, residing at Milwaukee, in the county of Milwaukee and State of Wisconsin, have invented a new, original, and ornamental Design for Paper Doilies, of which the following is a specification, reference being had to the accompanying drawing, forming part thereof.

The figure is a plan view of a paper doily, showing my new design.

I claim:

The ornamental design for a paper doily, as shown.

FRED CONRAD.
